JOSEPH MARTIN SCHUTZ, OF CHICAGO, ILLINOIS, ASSIGNOR, BY MESNE ASSIGNMENTS,
TO CHARLES GILBERT HAWLEY, OF CLEVELAND, OHIO.

ART OF BURNING FUEL.

Application filed September 6, 1923. Serial No. 661,163.

My invention relates to the combustion of fuels and has special reference to the burning of pulverulent or comminuted coals of all kinds, ranging from wood and peat, 5 through the lignite and bituminous groups, and including cokes and anthracite coals.

My purpose in this invention is to provide a simple, safe, efficient and easily controlled continuous process of burning fuel for the 10 rapid production of heat at high temperatures; and, a particular object is to speed up and ensure the better working of the process of combustion that is described and claimed in Patent No. 1,306,233 of June 10, 1919. It 15 will presently become apparent that the old and the new processes have much in common. Both are conducted within an upright annulus or burner proper that is open at the top, and which is closed at the bottom save 20 for a comparatively small slag discharge opening.

In the older process both the air and the fuel are introduced tangentially at the top of the annulus and whirl against the inner 25 walls thereof and downward toward its bottom, meantime taking fire, and the products ultimately react and return upwardly along the central axis; the flame rising from the lower part of the annulus and discharging 30 through its open top.

In my present improvement only the air is introduced tangentially at the top of the annulus. The coal is introduced close to the bottom, or as I herein call it, the circular 35 hearth. The active combustion is initiated on such bottom or hearth and is there completed to the point of fuel decomposition and the melting out or separation of the fuel ash.

40 In form, the resultant fire is much the same as that derived from the patented process, but is greatly accelerated and intensified; and is sharply localized on the bottom or hearth of the annulus; the means to that end 45 being the important new step of highly pre-heating the entering air before it reaches the fuel particles in the burner. This pre-heating of the air, I accomplish within the burner itself.

50 The whirling of the air and gases on the hearth very definitely holds back the particles of coal and coke from the central ash opening, allowing only the liquefied ash to discharge therefrom; and also plays an im- 55 portant part in respect to the spreading and

control of the entering air and in respect to the discharging flame.

In this invention, as contrasted with the old, the whirling column of air (generated by the tangential twyers) which drives downward onto the periphery of the hearth, is relieved from the duty and burden of spreading and holding the fuel particles on the vertical walls of the annulus, leaving said walls free to perform, in conjunction with the outgoing central body of flame, the new and important office of preheating the supplied air to a temperature approximating that of the flame. And thus before the air reaches the fuel on the hearth it is preheated 60 to a temperature so high as to ensure the almost instantaneous combustion of the fuel at the moment of admixture therewith; markedly hastening the performance of the complete process; or reversely, greatly increasing the capacity of a burner or annulus of given size.

Still further objects and features of the invention will appear hereinafter.

My invention will be readily understood 65 on reference to the following detailed description and the accompanying three sheets of drawings. In the latter, Figs. 1 and 2 are respectively vertical and horizontal sectional views of an apparatus or fuel burner 70 that I have devised for the working of this invention or process. Fig. 1 is a section on the line 1—1 of Fig. 2, and Fig. 2 a section on the irregular line 2—2 of Fig. 1. Figs. 3 and 4 are vertical and horizontal sections on 75 respectively indicated planes or lines (3—3) and (4—4) illustrating the best form of apparatus that I have thus far invented for carrying out my novel process and partic- 80 85 90 95 95 100 100 105 110

ularly designed to enable the use of an im- 95 portant step and effect not so well provided for in the burner of Figs. 1 and 2. The 100 particular structure illustrated in Figs. 3 and 4 is more fully described and is separately claimed in my companion application S. N. 661,164 entitled "Fuel burners", of even date herewith.

Referring to Figs. 1 and 2, the vertically disposed annulus or burner will be seen to be substantially circular in horizontal cross 105 section. It is preferably composed of a refractory material such as fire brick, and, is preferably constructed within and protected by an imperforate metal shell 2. The annulus proper comprises the circular or cyl-

inder wall 3', plus the bowl-like bottom or hearth 4, before mentioned. The slag discharge hole 5 is located at the center of the hearth. 6 represents the large flame discharge opening at the top of the annulus. The only real top portion that the annulus need have comprises the overhanging air-abutment ledge or ring 7, preferably also of refractory material.

- 10 Directly above the hearth 4, I introduce the comminuted or pulverulent coal or other fuel to be burned, using by preference a plurality of twyers 8 or supply pipes for the purpose. For sake of clearness, and it being understood that the comminuted fuel may be easily introduced through the agency of air blasts through the pipes 8, I have shown the twyers 8 in tangential relation to the periphery of the hearth. Thus positioned the 20 twyers have an initial effect in circumferentially distributing or spreading the fuel on the hearth, but the fuel may be introduced radially through the walls of the hearth or in any other desired manner, for as herein-after explained the force of the whirling supply of combustion supporting air is amply sufficient to uniformly distribute the fuel particles about the periphery of the hearth. Most conveniently the hearth takes the form 30 of a shallow bowl which has sufficient height to let the fuel through openings slightly above the floor of the hearth, where the fuel ash is liberated and liquefied.

- In some cases a part of the air required 35 for the combustion of the fuel may be introduced into the fire chamber 9 above the burner, such air feed being determined according to the kind of fuel burned and the degree of combustion required in the burner. 40 For the purposes of this description the whole or the greater part of the air required for combustion may be treated as being introduced through the burner. It is introduced in such manner as to form a downwardly moving and rapidly whirling hollow column.

- The air enters the burner under a pressure considerably greater than that in the fire chamber 9 and its introduction in the whirling manner described may be accomplished 50 in various ways and by various means. The simplest means comprise the overhanging ledge or abutment ring 7 and a plurality of tangential air twyers 10 which penetrate the 55 wall of the burner directly beneath the ledge 7. The pressure air, in the structure illustrated, is supplied from a suitable source through the pressure trunk 10' and thus freely enters all of the twyers 10 with substantially uniform pressure and velocity. Entering thus, the streams of air from the twyers encounter the cylindrical wall 3' of the burner and the centrifugal force set up causes the streams to press against that wall. 65 As egress upwardly is blocked by the abut-

ment ledge 7 the whirling blasts of air are forced to descend toward the bottom of the burner, describing spiral paths that may be likened to the low-pitched threads of a screw. Thus the air supplied for the combustion of the fuel is forced to make many turns within the burner and to travel from top to bottom thereof before coming in contact with the fuel on the hearth. It being understood that the mixture of fuel is ignited within the burner, it will also be understood that very quickly a rotating flame of large volume and great intensity is generated and continuously maintained on the bottom of the burner and at its axis. That bottom being closed, except for the small slag hole 5, the flame of necessity finds escape at the top of the burner through the large opening 6. The whirling motion of the air and gases within the burner is depicted by the spirally formed set of arrows in Fig. 2. The downward sweep of the air within the burner and the upward sweep of the flames and gaseous products of combustion are well represented by the two sets of arrows in Fig. 1. The outward throw or whirling of the flames and gases at the mouth or top of the burner, as depicted by these arrows, is caused by the terrific whirling of the products within the burner, which whirling and resultant centrifugal action, persists as the flame emerges from the top of the burner.

Having thus visualized the presence of combustion and the action of the upwardly moving body of flame within the burner, it will now be apparent that the freshly entering air from the twyers 10 moves circularly and spirally within the burner for a great distance and that throughout such travel the thin wall of air is directly in the presence of and exposed to the central body of the flame. Some of the supplied air doubtless more or less directly enters into combination with the richer products of combustion upon the exterior of the whirling central body of flame, but the greater quantity continues to the bottom and receives a full quota of heat both from the combustion going on in the burner and the hot walls. Hence for all practical purposes it may be said that before it reaches the bottom of the burner the air is heated almost to the temperature of the flame itself. It follows that the fuel particles attacked by air at such temperatures are consumed almost instantly, passing through all of the stages of decomposition and combination with almost explosive rapidity at the bottom of the burner or furnace. Obviously the walls of the burner normally are kept at a white heat, incandescent, and in the presence of these walls and the direct heat of the combustion, the freshly entering fuel is brought to a high temperature before the highly pre-heated air is admixed therewith. In this

manner and through these two effects the combustion is caused to take place with extreme rapidity and taking place within the limited confines of the burner, results in

5 temperatures which ensure the uniform continuity of the combustion even under widely varying feeds of air and fuel. Further, the closely localized combustion at these temperatures ensures the fusing and liquefying 10 of the incombustible solids or ash of the fuel, resulting in its complete separation from the combustibles. Due to its weight and viscosity the molten ash, or as it should now be termed, the slag, adheres to the floor 15 of the hearth and as it accumulates, flows to the center of the burner and discharges through the central opening 5.

Attention is called to the small arrows 5' in Fig. 1. These are intended to represent 20 the working of the burner or furnace at such internal pressure as will cause a slight lapping downward of flame at the margin of the slag hole, this being done to avoid possibility of the chilling of the slag thereon, 25 which if permitted would ultimately close the opening and require that a new opening be punched or made at the center of the hearth. The operation of the burner at such internal pressures may be disregarded 30 when the slag opening communicates with a tightly closed chamber that prevents an upward flow of cold air through the slag opening. Such a flow would chill or solidify the slag and is to be avoided.

35 My invention comprehends the varying of the distance between the air twy whole and the coal twy whole in relation or proportion to the diameter of the burner, to either increase or decrease the time of the exposure of the air 40 to the preheating action of the burner walls and its content of flame. It is proper to call attention to the regulation of temperature for the reason that some grades of coal contain ashes which fuse at very low temperatures and for such coals it is desirable 45 to limit the temperature at the bottom of the burner and thereby prevent the vaporization of the ash, which notwithstanding the forcible centrifugal action to which all of 50 the products are subjected might result in permitting such vapors to be discharged with the flame and to be thereafter condensed by contact with relatively cool surfaces in or about the fire chamber 9.

55 Further it should be noted that as the diameter of the burner is increased in relation to the distance between the air and fuel twy whole, the burning products are allowed 60 freer egress. This lessens the time that a given fuel particle and its products remain in the burner and hence affects the ultimate temperature therein. By proportioning the burner height and depth it easily may be adapted to any fuel; and likewise, may be 65 adapted to the burning of any given quality

of fuel within a given time. The temperature within the furnace or burner is also to be controlled by varying or proportioning the supplies or feeds of air and fuel.

For the purpose of further indicating that my invention is not limited to a specific structure, I call attention to the fact that by enlarging the burner toward the bottom, more or less as shown in Fig. 1, the need of the overhanging ledge or air-abutment ring 75 7 may be minimized and if desired the use of such a distinct abutment may be entirely avoided. The enlargement of the furnace toward the bottom affords the relief in that direction as opposed to the upward direction, which latter would permit the air to escape from the burner without first being admixed with the fuel on the hearth. In practically all these burners some of the air may escape directly at the top, but as before 80 indicated it is not necessary that all of the air shall descend to the bottom of the burner.

85 The crushed or comminuted coal supplied to the hearth of the furnace always contains many fine particles. To start the process into operation it is only necessary to apply a torch or kindling of any suitable kind within the bottom of the burner. Then the air blast is started through the top twy whole. Instantly an energetic fire is organized, and then the streams of fuel are admitted through the feed twy whole 8. The addition of the fine fuel to the fire further augments the latter and within a few minutes the inner 90 walls of the furnace are brought to incandescence and a flame body of size and temperature sufficient to take care of the full supply of fuel is established.

95 I shall now refer to Figs. 3 and 4 of the drawing.

100 It is desirable that the air which enters the burner shall be brought to a high temperature as quickly as possible. From the standpoint of a burner or furnace, which shall be adapted for use within a limited space, it is desirable that the depth of the burner shall be reasonably shallow. Again, it is desirable that the air which enters the burner shall be caused to whirl therein with the least obstruction to its movement and shall be permitted to attain the highest whirling velocity consistent with the pressure at which it enters, to the end that sufficient centrifugal force shall be developed 110 on the hearth to surely retain the fuel at the periphery thereof and thus prevent loss of fuel either downward through the slag hole or upward with the central body of flame. For the concurrent attainment of 115 these objects and conditions, in carrying out my process, I preferably employ an air twy whole construction which divides the air supply into a great number of thin sheets or streams that are disposed tangentially to 120

125 130

the body of the burner and are substantially parallel to the axis thereof. The thin streams or sheets thus entering the burner lap one over the other, and as they circle 5 within the burner constitute an annulus moving downward upon the hearth. The organization and preservation of the supplied air in this form of a thin walled annulus, obviously serves to ideally present the 10 air for the rapid reception of the heat of the central column of flame, the heat being received directly therefrom and from the hot surfaces against which the incoming air moves. The rapid heating of the air being 15 assured, it follows that its vertical movement or path within the burner, may be shortened, and the burner as a whole may be proportionately of less depth than a burner of the kind shown in Figs. 1 and 2. And, 20 as an exact centrifugal control of the whirling air must needs result in causing the lower end of the continuous column of air to descend upon the hearth at a maximum whirling velocity, it follows that the particles of coal on the hearth will not only 25 be certain to be set into rotation thereon, but that such movement will be maintained at velocities that develop in such particles sufficient centrifugal force to hold them 30 at the periphery of the hearth, against the inward pushing forces of the air and gases that react inwardly and upwardly from the hearth; and thus the escape of fuel at the slag hole is prevented.

35 For the reasons here explained the rotating organization of the described thin walled annulus or hollow column of air constitutes a very desirable step of my process.

Figs. 3 and 4 illustrate one such twyer 40 construction and the effect which it has upon the general construction of the burner or furnace. This twyer construction comprises a ring or annulus that is made up of a large number of upright metal blades, 45 vanes or flights, 11, separated by narrow slits or spaces 12; all inclined or curved in the same direction; and all, as nearly as feasible, at true tangents to the inner periphery of the ring which they constitute. 50 Practically the height of the vanes and hence the height of the tangential twyer ring as a whole, is or may be substantially the same as the height of the surrounding pressure-air trunk 13. The latter is of sufficient capacity to insure a substantially uniform pressure at each of the elongated narrow slits or twyers proper 12, and, of necessity, the air passing inwardly through the twyers is organized into the described thin 55 walled air column whirling at such velocity and with such centrifugal force as to bank against the inner periphery of the twyer ring, and to forcibly seek escape at the top and bottom thereof. At the top, escape is 60 cut off by the overhanging abutment ring or

ledge 14. At the bottom its escape is permitted, for there the descending whirling column directly enters the bowl-like hearth 15 and through many whirling motions finally approaches the axis of the burner 70 and finds relief upwardly through the open top of the burner; or in other words, is permitted to escape upwardly through the continuously maintained hollow annulus of air at the twyers. By these steps the above defined purposes are accomplished with the desired effects.

The fuel is admitted to the bowl 15 through one or several fuel twyers 16, which as suggested in Figs. 3 and 4 may be disposed radially or in any other desired relation, so long as the fuel is continuously fed upon the hearth. The actual feeding of the fuel may be done by blasts of air or other gas in the twyer pipes, or it may be fed by 80 any other force, including inspiration and the forces of any suitable mechanical feed mechanism. As before stated, it is only necessary to deliver the fuel upon the hearth. From that moment, it is carried forward and 85 properly distributed by the whirling air and gas within the burner.

My invention is not strictly limited to the burning of coal, but also includes the burning of various fuel oils and gases; both to 90 the end that the process may be worked alternately with such fuels, and to the end that the latter may with convenience be used for starting or kindling the coal fire on the hearth. I have not herein shown large gas 100 twyers such as may be employed at the margin or periphery of the hearth, but as representing both oil and gas feeds have depicted the use of the additional fuel twyers 17, the same appearing in both Figs. 3 and 4. Obviously, any suitable means may be employed to supply or feed the fuel to such alternative or additional twyers.

In other respects, the process as practiced in a burner of the construction of Figs. 3 110 and 4, does not differ from the practice with burners of the kind shown in Figs. 1 and 2; and therefore it seems unnecessary to here repeat the description of the elementary steps of the process as specifically related to 115 a shallow burner of the kind shown in Figs. 3 and 4.

Having thus described my invention, I claim as new and desire to secure by Letters Patent:—

1. The herein described improvement in the art of burning fuel, that consists in organizing a vertically extended thin walled hollow column of air in whirling downward motion and continuously maintaining the 125 same by the supply of fresh air thereto in tangential streams of sheet-like form entering the upper part of said column and substantially paralleling its axis, injecting fuel at the lower end of said column for combustion 130

with the air arriving at that point in highly preheated condition and meantime maintaining combustion axially within said column.

2. The herein described improvement in the art of burning ash containing fuels that consists in organizing a vertically extended thin-walled hollow column of air in whirling downward motion and continuously maintaining the same by the supply of fresh air thereto in tangential streams of sheet-like form substantially paralleling its axis, injecting fuel at the lower end of said column for combustion with the air arriving at that point in highly pre-heated condition, maintaining ignition and prolonging the

combustion upwardly within said column and draining the ash from the foot of said column.

3. The herein described improvement in the art of burning fuel that consists in forming and feeding a hollow whirling column of air downward in the presence of a flame axially within said hollow column, feeding fuel to the lower downward moving part of said column and admixing the same with the then heated air, igniting the mixture from said axial flame and permitting the burning mixture to escape along the axis of said column.

JOSEPH MARTIN SCHUTZ.
